UNITED STATES PATENT OFFICE.

FRANK DANIELSON, OF CHICAGO, ILLINOIS.

MOTOR STAND.

Application filed June 17, 1920. Serial No. 389,655.

To all whom it may concern:

Be it known that I, FRANK DANIELSON, a citizen of the United States, residing at Chicago, in the county of Cook and State 5 of Illinois, have invented a certain new and useful Improvement in Motor Stands, of which the following is a full, clear, concise, and exact description, reference being had to the accompanying drawings, forming 10 a part of this specification.

This invention relates to motor stands for engines and more particularly to a clamping means for internal combustion engines adapted to securely hold the engine in a plurality of positions to facilitate various operations thereon.

The invention further relates to a rotatable stand or table for clamping an internal combustion engine thereto in such positions as are necessary to facilitate the various operations to which said engine is subjected in the repair thereof.

The invention more particularly relates to improved clamping means on said rotatable table and an improved mounting of said table on the base of the machine whereby the table can be non-rotatably held in a plurality of positions.

Further objects and advantages of my invention will appear as the description of the accompanying drawings proceeds, in which—

Fig. 1 is a side elevation of the improved motor stand, showing the engine in one position in dotted lines;

Fig. 2 is a top plan view thereof;

Fig. 3 is a section through the rotatable table and associated parts taken on the line 3—3 of Fig. 2, and showing the engine in another position in dotted lines;

Fig. 4 is a fragmentary detail view of the base plate at the right hand end of the machine with the rotatable table removed, and

Fig. 5 is a section taken on the line 5—5 of Fig. 3.

The improved motor stand comprises a base 6 having secured thereto by bolts the bed 7. The bed 7 has mounted on one end thereof a vise 8 which does not form a part of this invention and on the other end thereof is mounted a table 9 which is mounted for rotation on the bed 7. The revolving table 9 which serves as a support for an engine cylinder block is provided with a number of projections to suitably support the

engine block in various positions. For the purpose of holding the engine cylinder block in the position shown in Fig. 3 when it is on its side, the projections 10 are provided along one of the edges of the table 9, these being suitably grooved to conform to the curvature of the sides of the engine cylinders, so that the cylinder block 11 shown in dotted lines in Fig. 3 will be held therein. The flange 12 provided at the base portion of the cylinder block is held between a pair of projections 13 at the opposite edge of the table and a somewhat shorter projection 14 spaced inwardly from the edge 70 of the table. The projections 13 and 14 being on opposite sides of the flange hold the cylinder from movement transversely of the support.

In order to firmly clamp the cylinder block to the support a clamping member 15 is provided. The clamping member 15 has a hook-shaped extremity 16 that engages over the inner edge of the opening in the base of the cylinder block and at its other end is provided with a downwardly extending projection 17 that bears on the supporting member 9. The clamping member 15 is provided with a clamping screw 18 having screw threaded engagement with the clamping member and on the lower end portion of the clamping screw 18 is mounted a square block 19 which is suitably keyed thereto to prevent rotation between the block 19 and screw 18. The screw 18 extends through a slot 20 in the engine supporting table and this slot has an enlargement 21 through which the block 19 may be inserted or withdrawn in order to either place the clamping member 15 in position or to remove the same from the engine supporting table.

It will be noted that the shank portion of the hook end 16 of the clamping member 15 shown in Fig. 3 is somewhat shorter than that shown on the hook end 16' of the clamping member 15' in Fig. 1, it being necessary to have clamping members with different lengths of the hook portions in order to clamp the engine cylinder block in various positions.

It will be seen that with the arrangement described one of these clamping members can be readily removed and another one substituted for the same.

When the engine is in the position shown in Fig. 1 the same is in an inverted posi-

tion with the upper ends of the cylinders down. When in this position the motor rests on the lugs 13 and on the lug 22, thus giving a three point support for the engine. It will be noted that in this position of the engine the lug 14 does not contact with any portion of the engine as the same is shorter than the lugs 13. The hook end 16' of the clamp 15' used when the engine is in this position engages under the projecting water jacket 23 of the engine cylinder block to securely hold the same on the supporting table. The supporting table is provided with a projection 24 which is in the path of movement of the downwardly extending projection 17 of the clamping member 15 to limit the rearward movement thereof.

The table 9 is provided with suitable ribs 20 25 which act as guides for the block 19 to aid in properly guiding the clamping member 15 in its sliding movement on the table.

The table 9 is provided with a suitable downwardly extending cylindrical boss 26 which is adapted to seat in a corresponding recess 27 in the bed 7. This permits the table 9 to rotate in the circular socket 27 on the bed. The table 9 is also provided with a circular rib or rim 28 and the bed 7 is provided with a corresponding rib or rim 29 facing the rib 28. The rib 29 is provided with recesses 30, of which any suitable number may be provided, four being shown in the drawings, and a rib 28 is provided with projections 31 corresponding in number to the recesses 30 and adapted to seat therein when the same are in alignment.

The bed 7 is also provided with a downwardly extending elongated extension 32 provided with an opening to receive a bolt 33 which bolt extends through an opening 34 in the table 9 and has a square head 35 seated in a corresponding recess in the table 9 to hold the bolt against rotation relative to the table 9. The lower end of the bolt 33 is screw threaded and is provided with a hand wheel 36 which is internally screw threaded and adapted to engage against the extremity of the projection 32.

It will thus be seen that when the lugs or projections 31 are seated in the recesses 30 and the hand wheel 36 is turned so as to draw down the table 9 relative to the bed 7, the projections will be firmly seated in the recesses and will hold the table 9 from rotation about its pivot. This provides a very secure clamping means that does not require the exertion of any great amount of force to actuate the same. It will be seen that with the number of projections and recesses provided four different positions of the table are possible and that the number of different possible positions can be increased depending upon the number of lugs and projections used and the proper spacing of the same.

It will thus be seen that a rotatable engine supporting table is provided that can be suitably locked in a plurality of different positions and which is adapted to hold the engine cylinder block thereon in a plurality of 70 positions.

It is also seen that a clamping means for the engine cylinder block is provided, which is readily interchangeable to permit its use with the position of the engine cylinder block for which it is suitable.

Having thus described my invention I desire to have it understood that I do not intend to limit myself to the particular forms shown and described except as defined by the following claims:

1. A device of the character described comprising a horizontal, rotatably mounted bed, projections rigid with the bed and distributed thereon to support an engine cylinder block in a plurality of positions, a detachable clamping element and means for guiding said clamping element whereby the same is longitudinally slidably mounted in said bed for clamping said cylinder block thereto, said clamping element and bed being provided with cooperating means to limit the outward sliding movement of said element.

2. A device of the character described comprising a bed, projections on said bed distributed thereon to support an engine cylinder block in a plurality of positions, and a detachable clamping element longitudinally slidably mounted in said bed for clamping said cylinder block against certain of said projections, said clamping element having an angular jaw portion having a plurality of faces engaging said cylinder block.

3. A device of the character described comprising a bed, projections on said bed and distributed thereon to support an engine cylinder block in a plurality of positions, and a detachable clamping element longitudinally slidably mounted in said bed for clamping said cylinder block thereto in each of said positions, said clamping element and bed being provided with cooperating stops to limit the outward sliding movement of said element.

4. A device of the character described comprising a bed, projections on said bed and distributed thereon to support an engine cylinder block in a plurality of positions, said bed being provided with a slot therein and a clamping member on said bed having a projecting portion extending through said slot, and an angular block on said projecting portion whereby said clamping member is mounted for guided longitudinal sliding movement on said bed.

5. A device of the character described comprising a bed, projections on said bed and distributed thereon to support an engine cylinder block in a plurality of positions,

5 said bed being provided with a slot therein and a clamping member on said bed having a projecting portion extending through said slot, and a block on said projecting portion whereby said clamping member is mounted for guided longitudinal sliding movement on said bed, said clamping element and bed having cooperating stops to limit the sliding movement of said element in an outward 10 direction.

6. A device of the character described comprising a bed, projections on said bed for supporting an engine cylinder block, said bed being provided with a slot therein 15 having an enlargement at one end thereof, and a detachable clamping member on said bed having a projecting portion extending through said slot, and an angular block on said projecting portion adapted to be passed 20 through the enlargement in said slot, whereby said clamping member is detachably mounted for guided longitudinal sliding movement on said bed.

7. A device of the character described 25 comprising a bed, projections on said bed for supporting an engine cylinder block, said bed being provided with a slot therein having an enlargement at one end thereof and a detachable clamping member on said 30 bed having a projecting portion extending through said slot, and an angular block on said projecting portion adapted to be passed through the enlargement in said slot, whereby said clamping member is detachably 35 mounted for guided longitudinal sliding movement on said bed, said enlargement being at the end of said slot adjacent said projections.

8. A device of the character described 40 comprising a bed, means on said bed to support an engine cylinder block in a plurality of positions, said supporting means having a cylindrical extension on its under side and said bed having a circular recess cooperating 45 therewith to rotatably mount said supporting means on said bed, and means for positively locking said supporting means on said bed in a plurality of positions, said means comprising cooperating projections 50 and recesses on said supporting means and bed.

9. A device of the character described comprising a bed, means on said bed to support an engine cylinder block in a plurality 55 of positions, said supporting means having a cylindrical extension on its under side and said bed having a circular recess cooperating therewith to rotatably mount said supporting means on said bed, a bolt non-rotatably 60 mounted in said supporting means, and a hand wheel having screw threaded engagement with said bolt and adapted to engage

a portion of said bed to clamp said supporting means on said bed.

10. A device of the character described 65 comprising a bed, means on said bed to support an engine cylinder block in a plurality of positions, said supporting means having a cylindrical extension on its under side and said bed having a circular recess cooperating 70 therewith to rotatably mount said supporting means on said bed, said bed and supporting means having cooperating recesses and projections and clamping means to seat said projections in said recesses, whereby 75 said supporting means can be locked against rotation in a plurality of positions.

11. In a device of the character described, a bed, a rotatable table mounted on said bed, said bed having a circular recess therein, a 80 central downwardly extending cylindrical extension on said table seated in said recess and having a central bore, a circular rim on said table concentric with said extension, a similar rim on said bed, said rims having 85 cooperating recesses and projections, a bolt mounted in said bore and extending through said bed, means to hold said bolt against rotation, and a hand wheel having screw threaded engagement with said bolt, whereby said projections are caused to seat in said recesses to hold said table against rotation on said bed in a plurality of positions.

12. A device of the character described 90 comprising a bed, projections rigid with said bed and distributed thereon to support an engine cylinder block in a plurality of positions, and a clamping element longitudinally slidably mounted in said bed, said clamping element having a depending projection and said block having a lip adapted 95 to be engaged by said projection to limit the outward sliding movement of said element.

13. A device of the character described 100 comprising a bed, projections on said bed for supporting an engine cylinder block thereon, and a member for clamping said cylinder block on said bed comprising a body portion and a holding jaw having cylinder block engaging faces extending substantially at right angles to each other.

14. A device of the character described 105 comprising a bed, projections on said bed for supporting an engine cylinder block thereon, and a member for clamping said cylinder block on said bed comprising a body portion and a holding jaw having a portion extending substantially at right angles to said body portion and an overhanging lip extending substantially at right angles to said first mentioned portion.

In witness whereof, I hereunto subscribe my name this 7th day of June, A. D. 1920.

FRANK DANIELSON.
